DEVICE FOR TREATING TEXTILE FABRICATIONS ON FORMS

Walter M. Schwartz, Philadelphia, Pa., assignor
to Proctor & Schwartz, Incorporated, Philadelphia, Pa., a corporation of Pennsylvania

Application March 30, 1940, Serial No. 327,086

30 Claims. (Cl. 223—76)

This invention relates to a machine for processing fabricated textile articles including hosiery and other items of wearing apparel, etc., to set the shapes of the articles. The present invention relates particularly to articles made of filaments, threads, or yarns composed of what is known as "Nylon."

Normally, silk, rayon or other hosiery in the grey, i. e. hosiery which has been knitted, looped, seamed, etc., and before it is dyed, boarded, and finished, is tied in loose bundles or placed loosely in mesh bags for dyeing in bulk, after which each stocking is dried and subsequently boarded, i. e., each stocking is placed on a form having the contour which the stocking is to attain during and subsequently retain after finishing. The boarded stockings are dried and finished on the shaping forms, with or without being moistened prior to ultimate drying on the forms.

A stocking composed of natural silk, rayon, or any of the other types of thread or yarn commonly used in the manufacture of hosiery, will retain the shape of the form on which it is dried, after the stocking is removed from the form. However, a stocking made of "Nylon" when dyed, boarded, and finished in the usual manner above noted, will not retain the shape of the finishing form or board. After a Nylon stocking is removed from the board it returns almost immediately to a crumpled, disheveled, unshapely condition similar to that which it had while in the grey, or before it was finished on the board.

It has been found that the above-noted reversion can be avoided by putting "Nylon" hosiery, while in the grey or before regular boarding and finishing, through a preliminary or preboarding process for "setting" the yarn fibre or filament structure. This is done by placing the undyed or unfinished hosiery on forms similar to those on which the hosiery is placed for the regular finishing process, to give shape to the flaccid fabric prior to setting the yarn structure thereof.

The above noted preliminary treatment or setting process is accomplished by exposing the form-supported "Nylon" stockings to heat, for a given period of time. The best results appear to be obtained by exposing the form-supported hosiery to live steam under a pressure, for example, of approximately ten pounds per square inch, for a period of approximately five to ten minutes. After steaming, the hosiery is permitted to remain on the preliminary shaping or setting boards for a period of approximately five minutes, or upward, while exposed to normal atmosphere or to an artificially created atmosphere of 55

predetermined temperature and humidity to permit the hosiery to cool, dry and otherwise attain a handleable condition, before removing the stockings from the forms. It will be understood that the pressure and time figures etc. noted above are given merely as examples and are not to be considered absolute. Furthermore, the character of the steam may vary from a dry condition to a rather wet condition. Steam of an intermediate moisture content appears to be preferable.

If the hosiery has been preboarded and set while in the grey, it is then removed from the preliminary setting boards, bundled or bagged in bulk, dyed, dried, then re-boarded and finished in the regular manner thereafter. Nylon hosiery, having undergone the preliminary "setting," supra, before final boarding and finishing in the regular manner, will attain and retain the shape of the finishing form, and will have a sleek, smooth-finished appearance and condition comparable to finished hosiery composed of the usual materials.

If dyed before preboarding and setting, the hosiery may be retained on the setting boards or forms and, after completion of the pre-setting operation, passed directly through the regular finishing process.

The present invention has to do with a machine for accomplishing the "setting" process. Prior to the present invention, a machine known and used for the purpose consisted of a turret head rotatable about a vertical axis, with three radially projecting angularly spaced groups of forms respectively extending horizontally from the axis of the turret for intermittent movement to three different stations successively. At the first station, previously set hosiery was removed from one group of forms and new unprocessed hosiery placed thereon. The turret then moved the newly loaded group of forms to a second, or setting, station, in alignment with a horizontal cylinder closed at its outer end and open at its inner end to receive the newly loaded group of forms. By relative radial movement between the cylinder and the turret, the group of forms aligned with the cylinder passed into the cylinder and a steam-tight joint was formed between the open end of the cylinder and the turret head. Steam was admitted to the cylinder and maintained under a predetermined pressure therein for a given period of time. During this time the group of stocking-laden forms which was previously confined in the cylinder and which moved to the cooling station was permitted to stand at

that station in the open, to cool, dry, etc., while the third group arrived and remained at the initial, or loading, station, for removal of the steamed, cooled and dried hosiery therefrom and the application of unprocessed hosiery thereto.

Upon completion of a period of elapsed time necessary for the operator to remove the processed hosiery from the forms at station one, or longer, the steam was exhausted from the cylinder at station two, the seal between the cylinder and the turret head was broken, and the group of forms in the cylinder was withdrawn therefrom. The turret was then moved one step manually, to bring the newly processed group of hosiery to the third, or cooling, station, while a new group moved to the setting station, two, in line with the cylinder, from the loading station, one, for a repeat of the cycle.

The above noted machine had many disadvantages, including excessive floor space requirements, inefficient and inconvenient loading and unloading facilities, loss of time in making and breaking the steam-tight seal between the open end of the pressure cylinder and the turret head, and others of greater or lesser importance.

The object of the present invention is to construct a machine which will successfully replace the turret type machine and eliminate each and all of the faults of the turret-type machine, i. e. the object of the present invention is to reduce the floor space requirements, increase the capacity, provide efficient loading and unloading facilities, speed up the making and breaking of the steam chamber seal and correlate the various operations of the machine in a manner to reduce the time necessary to complete the processing cycle for a group of stockings to a minimum; whereby a manufacturer having a finishing plant of given hourly capacity for regular goods will be required to install but a minimum amount of additional equipment and employ but a minimum number of additional operators to effect the pre-setting of "Nylon" hosiery in order to keep pace with the hourly capacity of his regular equipment.

The preferred embodiment of the present invention involves the use of a steaming chamber in the form of a bell or dome having its axis always disposed vertically with the bell arranged for perpendicular movement relative to a fixed horizontal base, against the upper surface of which the rim of the open lower end of the bell is adapted to be seated and sealed for and during the steaming of a number of stockings respectively mounted on vertically disposed setting forms supported on said base within the bell-shaped chamber.

Mechanism is provided for lowering the bell into sealing contact with the base and to raise the bell-shaped steaming chamber until the sealing rim thereof is spaced sufficiently above the sealing surface of the base to permit one group of setting forms to be moved horizontally along the base from the steaming position within the area covered by the bell to a position external thereto, for loading and unloading, while another group of stocking-laden forms is moved from an external loading and unloading position into alignment with the bell for the bell to be lowered around them into sealing contact with the base.

In a modified form of the invention the bell is raised to a position high enough above the top edges of one group of forms occupying a relatively fixed position on the base to permit the bell to be moved laterally into alignment with another group of hosiery-laden forms occupying a

correspondingly fixed position on the base in laterally spaced relation to the first said group of forms, in order that the bell may then be lowered into sealing contact with the base around the second group of forms.

5 In another modified form of the invention, two bells are used in axial alignment respectively with two groups of forms maintained in relatively fixed laterally spaced relation to each other on the rigid base with the two bells counterbalancing each other for and in alternately moving the two from closed to open position and vice versa, or the two bells may be independently and relatively moved to and from the closed position, if desired.

10 In each of the above cases, one group of forms will preferably be enclosed by the bell-shaped steaming chamber for steaming the enclosed hosiery while a second group of forms is positioned in the open for removal of the steamed stockings from the forms and the replacement of new unsteamed stockings thereon.

The constructions noted above enable the machine to be built so as to occupy and be operated within a minimum amount of floor space.

15 In order to maintain the size of the bell at a minimum and to place a maximum number of forms in the bell of minimum diameter or cross-sectional area, the forms are preferably closely nested circumferentially about a common axis, and in order to facilitate the loading and unloading of the forms the forms are preferably mounted on a turntable type of carrier, with the axis of the turntable coaxial with the common axis of the group and adapted to be coaxially aligned with the axis of the bell when the group of forms supported by the turntable is confined within the bell.

20 In order to provide sufficient room to enable the operator to strip a stocking from a form and place another thereon, with the back seam, for example, of a full fashioned stocking in line with the back edge of the form, each form is carried by an individual arm which is pivotally mounted on the turntable. Mechanism is provided to open-up the circumferential nesting of the forms at a given place in the rotation of turntable, at which the operator stands, so that two forms at opposite sides respectively of the operator's station lie in radially divergent relation to each other with another form in the clearing intermediate and substantially equidistant from the spread-apart forms, and each form is so mounted on its supporting arm that when it reaches the above noted "clear" position it may be rotated about its vertical axis to an extent approximately one hundred and eighty degrees.

25 The turntable is automatically rotated intermittently to bring the forms successively into the clear position for loading and unloading.

30 At a predetermined point in the rotation of the turntable carrying the group of forms being loaded and unloaded, the steam which has been passing into the bell then enclosing the other group of forms is automatically shut-off and exhausted from the bell; then, at another subsequent point in the rotation of the turntable carrying the group of forms being loaded and unloaded, the bell is automatically raised to clear the one group and to receive the other group of forms, after which the bell is again lowered into sealing contact with the base and the steam turned on to process the stockings on the newly enclosed group of forms while the operator strips and reloads the forms of the group which have

just been removed from the bell-shaped steaming chamber.

While in the steaming chamber, no rotation of the turntable carrier for the forms therein takes place. Mechanism is provided for automatically connecting the turntable of the group of forms when it is removed from the steaming chamber and for discontinuing rotation of the turntable when the last of the series of forms thereon has been stripped and reloaded.

In the accompanying drawings:

Fig. 1 is a side elevation of one form of apparatus constricted and operable in accordance with the principles of the present invention, with the upper portion of the bell tower omitted;

Fig. 2 is a sectional plan view taken on the line 2—2, Fig. 1;

Fig. 3 is an end elevation, with the upper portion of the bell in section;

Fig. 4 is an enlarged side elevation of the turntable truck in the loading and unloading position;

Fig. 5 is a plan view of the structure shown in Fig. 4;

Fig. 6 is a transverse sectional elevation taken on the line 6—6, Fig. 5;

Fig. 7 is a sectional plan view taken on the line 7—7, Fig. 6, with the form-supporting arms removed from the turntable;

Fig. 8 is a view similar to Fig. 7 but showing the second turntable supporting truck in position under the pressure bell, with the latter in its elevated position;

Fig. 9 is a sectional elevation taken on the line 9—9, Fig. 8;

Fig. 10 is a sectional elevation of a detail, taken on the line 10—10, Fig. 8 showing a resilient stop for the truck in the steam chamber;

Fig. 11 is a perspective view of a latch and stop for holding the truck stationary in the loading and unloading position;

Fig. 12 is a perspective view of one of the form supporting arms;

Fig. 13 is a perspective view of one of the form spacers which are rotatably carried by the form supporting arms and to which the forms are respectively secured;

Fig. 14 is an inverted perspective view showing part of a means for limiting rotation of each form relative to its supporting arm;

Fig. 15 is a diagrammatic plan view showing the relative locations of the various mechanical control devices of the machine;

Fig. 16 is a sectional elevation taken on the line 16—16, Fig. 15;

Fig. 17 is a transverse sectional elevation taken on the line 17—17, Fig. 7;

Fig. 18 is a sectional elevation of one type of steam control mechanism that may be used in the present machine;

Fig. 19 is an elementary electrical diagram showing the electrical controls diagrammatically;

Figs. 20, 21 and 22 are a side elevation, plan, and end elevation respectively of a modified form using a pair of bell shaped pressure chambers operating in counterbalanced relation to each other, with the bells at all times axially aligned with a pair of turntable form-supports respectively;

Fig. 23 illustrates another modification using two bells operable separately or in counterbalanced relation to each other and provided with means for suctionally evacuating steam from either chamber and saving a portion thereof for use in the other chamber, if desired.

Fig. 24 illustrates another modification where in the steam is evacuated and condensed;

Fig. 25 illustrates another modification where in the steam is condensed within the chamber itself;

Figs. 26, 27 and 28 respectively illustrate side, plan and end views of another modification using one pressure chamber and two turntables, with the pressure chamber arranged to be shifted from 10 alignment with one into alignment with the other of the turntables;

Figs. 29, 30 and 31 are views similar to Figs. 26, 27 and 28 with power means for shifting the bell;

15 Figs. 32, 33 and 34 show another form with a counterweight for the bell;

Figs. 35 and 36, show another form using an electric overhead crane for operating the bell;

20 Figs. 37, 38 and 39 illustrate another form wherein the bell is mounted on a post between two turntables, to be swung laterally into alignment with either; and

25 Figs. 40, 41 and 42 illustrate another form where two bells of smaller compass are raised and lowered simultaneously relative to two series of forms respectively.

As shown in Figs. 1, 2 and 3, the preferred form of machine comprises a rigid framework structure including a base 1 supported by pedestals 2, 2 which forms part of the framework. The framework also comprises a tower 3 composed of uprights 4, 4 and cross beams 5, 5 to which are secured bearings 6, 6 for rotatably supporting the upper ends respectively of vertically disposed screw threaded shafts 7, 7. The lower ends of the screw shafts 7, 7 are rotatably mounted in the pedestals 2, 2 respectively.

Secured to the opposite ends respectively of a pressure equalizing yoke 8 are nuts 9, 9 which 40 have threaded engagement with the screw shafts 7, 7 respectively, by which the bell-shaped pressure chamber 10 is raised and lowered perpendicularly with respect to the base 1, when the screw shafts are coordinately rotated simultaneously by worm gearing 11 in the pedestals 2 from a reversible motor 12.

The bell 10 is connected to the yoke 8 (see Fig. 3) by a ball and socket joint of which one element, for example the ball 13, is secured to the yoke while the other element, the socket 14 in this instance, is secured to and at the axial center of the top closure 15 for the cylindrical bell-shaped chamber 10, the lower end of which is provided with guide bearings 16, 16 which are secured to the bell 10 and are slidably mounted on nonthreaded portions 17, 17 of the screw shafts 7, 7 respectively to guide the rim of the bell into sealing contact with the base 1.

60 The rim 18 of the lower open end of the bell-shaped chamber 10 is provided with an annular groove 19 (see Fig. 9) for reception of a circular rib 20 formed on the upper substantially horizontal chamber closing surface 21 of the base 1. A packing strip 22 is carried in the groove 19 to cooperate with the rib 20 to form a steam tight seal between the rim 18 of the chamber 10 and the rib 20 of the base 1.

As noted above, the chamber 10 is adapted to 65 enclose a group or series 25 of individual stocking boards or forms 24, 24. The forms of each series are normally nested around a common center X, as shown in Fig. 5. Each form 24 is provided with a stem 26 (see Fig. 6) which is rotatably mounted in bearings 27 and 28 formed 75 on the outer end of a horizontal arm 30. The

inner end of each arm 30 is provided with vertically spaced axially aligned pivot studs 31 and 32 which are respectively mounted in bearing sockets 33 and 34 formed in vertically spaced axially aligned horizontal discs or rings 36 and 37 respectively which are rigidly joined together to form a turntable 35 for supporting the entire series 25 of forms 24, 24.

The turntable 35 is provided with a central hub 38 which is adapted to receive and rotate about a rigid vertically extending post 40. In the preferred form of the invention using one bell-shaped pressure chamber 10 and two series of forms 25 with the form series alternately movable into vertical alignment with the bell, the post 40 is mounted in a truck 50; whereas in that form of the invention wherein the form series are each retained in one position at all times and the bell is shifted laterally from alignment with one into alignment with the other of the two series of forms or where the two bells are respectively aligned with the two series of forms at all times, the post 40 is mounted directly in the base 1.

In each of the above noted instances, the turntable 35 is intermittently rotated about the axis of the post 40 to bring the forms 24, 24 successively to a station A (see Fig. 5) occupied by the operator, while the series of forms on the turntable is clear of the bell. As the turntable revolves and each form 24 approaches the operator's station A, a projection 41 (see Fig. 5) on the arm 30 which supports that particular form, strikes a projection 42 carried by a bracket 43 which is rigidly secured to the post 40 and extends outwardly therefrom above the turntable 35, and swings the form from its angular position at one side of the gap formed between two radially divergent forms, in which position the operator occupying the station A, adjacent said gap, may rotate the form substantially 180° for stripping a stocking therefrom, applying another thereto, and straightening the stocking thereon.

Prior to each form being swung from its nesting position at one side of the gap or clearing at the operator's station A into said intermediate position at the center of said gap, the preceding form then occupying said intermediate position will be moved therefrom into nesting position at the opposite side of said gap or clearing by cooperation of its projection 41 with the fixed projection 42.

In the present instance the cooperating projections 41 and 42 are in the form of gear teeth constituting segmental portions of gears whose pitch line arcs are swung from the center of the pivot studs 31 of the arms 30 and the post 40 respectively.

The gap at the operator's station A is formed in the nested group of forms 24, 24 by retarding the movements of the outer ends of the form supporting arms as the turntable revolves about the axis of the post 40. This is accomplished by a shoulder 44 (see Fig. 5) on each arm 30 engaging a fixed cam 45 carried by the fixed bracket 43. Such retardation also places the projections or teeth 41 of the arms 30 in correct position to engage the fixed projection or teeth 42 on the bracket 43, to swing each arm 30 into the intermediate clear position after the shoulder 44 thereon rides off the fixed cam 45. The movement of the turntable and pivot 31 of the arm 30 past the fixed projection or teeth 42 on the bracket 43 causes the intermeshing of the teeth to swing the arm 30 from the intermediate clear position to the position at the second side 75

of the clearance gap, into nesting relation to the preceding forms.

As each form swings from the intermediate clear position into nesting position, the form is rotated about the axis of its stem 26 by a short arm or finger 46 (see Fig. 6) secured to the lower end of the stem 26 making wiping contact with a fixed cam 47 (see Fig. 5) which is carried by the truck 50 or base 1, as the case may be, so that the toe portion 24a of each form 24 will be turned outwardly as the form nests against its predecessor.

The nested forms are spaced apart to prevent marring of the stockings by spacer plates 48, 48 (see Figs. 5 and 13) secured to the form stems 26, 26 respectively and the hub 49 of each of said spacer plates is cut out (see Fig. 14) for approximately one half its circumference on the underside of the hub adjacent the top surface of the stem bearing 27 of the arm 30, from which a pin or lug 51 (see Fig. 12) projects upward into the cut-out 52 of the hub 49 to be engaged by shoulders 53, 53 at the opposite ends respectively of the cut-out 52 to limit the rotary motion of the form relative to its supporting arm 30 so that the form cannot at any time assume such a position that its toe portion cannot be turned outwardly by wiping contact of the positioning finger 46 with the form positioning cam 47.

Intermittent rotation of the turntable 35 may be accomplished by any suitable means and in the present instance is effected by a Geneva movement (see Fig. 7), wherein the peripheral edge of the lower annular portion 36 of the turntable is provided with circumferentially spaced locking concavities 54, 54 alternating with tooth openings 55, the latter to cooperate with a single operating tooth 56 on and projecting outwardly from the circumferential edge 51 of a continuously rotating driving disc 58, the concavities 54 being formed each on a radius corresponding to the radius of the circumferential edge 51 of the disc 58 and adapted to lie in contact therewith during the intermittent quiescent periods of the turntable 35 between successive engagements of the tooth 56 with successive tooth openings 55 in the turntable, by which the turntable is advanced to an extent equal to the spacing of the form supports on the turntable to bring the supports successively to the operator's station A.

In instances where the turntable is mounted on a truck 50 for movement into and out of alignment with the bell 10 the disc 58 is secured to a vertical shaft 59 rotatably mounted in suitable bearings formed in or carried by the truck 50. Also secured to the shaft 59 is a spur gear 60 which, when the truck 50 and the forms carried thereby are moved out of alignment with the bell into the stripping and reloading position, intermeshes with a gear 61 (see Fig. 7) which is secured to a shaft 62 rotatably mounted in a lateral extension 63 of the framework of the machine. As shown in Figs. 1 and 2, there are two such lateral extensions and a gear 61 adjacent the outer end of each. There are also two trucks 50 so arranged that when one is in line with the bell 10, the other is in stripping position on one of the frame extensions 63 (see Fig. 2) with the gear 60 on the truck meshing with the gear 61 on the framework, and when the truck is moved into alignment with the bell the intermeshing relationship between the gears 60 and 61 is broken. The lower ends of the shafts 62, 62, which support and drive the gears 61, 61 respectively, enter gear boxes 64, 64 (see

Fig. 1). The lower ends of the shafts 62, 62 are connected by suitable gearing in said gear boxes 64, 64 with the opposite ends of a horizontal shaft 65, said shaft being driven from a motor 66 through a suitable speed changing device of conventional type 67, (see Fig. 2).

Each truck 50 is provided on each of its opposite sides with a series of four supporting wheels 70 spaced along the length of each side of the truck for riding rails 71, 71 supported by the base 1 and the lateral extension 63, 63 of the framework of the machine, said rails being interrupted under the rim 18 of the bell-shaped chamber 10 at each side of the sealing rib 20 on the base 1, as shown at 72 in Figs. 2 and 8, so as not to interfere with the proper sealing of the bell 10 and base 1. The spacing of the wheels 70, 70 is such that the trucks 50 pass smoothly from the sections of the rails 71, 71 lying within the area covered by the bell 10 to the sections lying outside the area covered by the bell 10, as the trucks 50 are moved from one position in vertical axial alignment with the chamber 10 to one of the operator's stations A, A, at either side of the chamber. Each truck is provided with an adjustable stop 124 adapted to engage a fixed stop 123 (see Fig. 8) on the base 1 to center the turntable 35 under the chamber 10. A pair of resilient stops 122, 122 in the rails 71 engage the outer wheels 70, 70 to retain the truck in centered position (see Fig. 10).

When in the stripping and reloading position, with the gears 60 and 61 in intermeshing relation with each other, the wheels 70, 70 on the outer end of the truck 50 engage adjustable stops 73, 73 carried by the framework 63 to prevent movement of the truck in one direction, while movement of the truck in the opposite direction is prevented by a latch 75 (see Fig. 11) engaging a suitable lug or one of the wheels 70 on the truck 50 so that the gears 60 and 61 maintain proper intermeshing relationship with each other, said latch being readily releasable by a foot treadle 74.

Steam is admitted to and exhausted from the interior of the chamber 10, when in sealing relation to the base 2, through a pipe 76 (see Fig. 9) tapped into the base 1 beneath the truck 50, which latter acts as a deflector or diffusing baffle for the steam entering the chamber.

Ingress and egress of the steam through the pipe 76 may be controlled in any suitable manner, for example through an electrically controlled valve, such as shown in Fig. 18. In this instance the pipe 76 is connected to a valve casing 77 to which is also connected a live steam pipe 78 and an exhaust steam pipe 79. A quick acting double valve element 80 is adapted to control the steam passage 81 through which steam passes from the live steam pipe 78 to the pipe 76 and a steam passage 82 through which the steam passes in exhausting from the pipe 76 into the exhaust pipe 79. The valve 80 is controlled in such a manner that when the passage 81 is opened, the passage 82 is closed and vice versa.

Any suitable mechanism may be provided for shifting the valve element 80 from one of its positions to the other quickly so as to prevent the escape of live steam in substantial quantities directly from the live steam feed pipe 78 to the exhaust steam pipe 79.

Operation of the valve 80 in the present instance is controlled through an electrically controlled pilot valve 85 (see Fig. 18). The valve element 80 is provided with a stem 83 which is secured to a diaphragm 84 spaced from a head 79

96 which closes the lower end of a chamber 86 leaving a space 97 between the two. A spring 87 encircling the stem 83 of the valve 80 tends at all times to move the valve element 80 downwardly to close the passage 81 and exhaust the steam from the pipe 76 through the passage 82. The live steam side of the valve chamber 77 is connected by a pipe 88 to a chamber 89 of the pilot valve chamber 85. The exhaust side of the valve chamber 77 is connected by a pipe 90 to an exhaust chamber 91 of the pilot valve 85. A reciprocating valve having one element 92 in the exhaust chamber 91 and the valve element 93 in the live steam chamber 89, is connected to a lever 94 which, in turn, is connected to the movable core of a solenoid 95.

Normally, when the solenoid 95 is deenergized the valve 92 is moved from its seat permitting steam to exhaust from the interior of the space 97, pipe 98 and chamber 91 of the pivot valve casing 85 through the exhaust pipes 90 and 79, whereupon the spring 87 moves the diaphragm 84 downwardly and seats the valve element 80 to close the live steam passage 81. As the valve 80 seats on the passage 81 it opens the exhaust passage 82 in the valve chamber 77, permitting the steam to exhaust from the pipe 76 into the pipe 79.

When the solenoid 95 is energized the valve 92 is seated and the valve 93 is unseated, permitting live steam to flow through the pipe 88, pilot valve 85 and pipe 98 into the space 97 and displacing the diaphragm 84 upwardly, causing the stem 83 of the valve element 80 to move said valve element into a position closing the exhaust passage 82 and opening the live steam passage 81, whereupon live steam flows from the feed pipe 78 to and through the pipe 76 into the chamber 10.

Each turntable is provided with a series of circumferentially spaced holes 100 into which control pins may be selectively inserted and secured in place in the turntable, for actuating various control switches automatically, to govern the operation of the machine as a whole. Additional manual switches and safety switches are provided in the circuit to take care of other operations, including emergencies, should necessity arise.

If the truck which is intended to be in vertical alignment with the pressure chamber is not properly centered below said chamber, the latter cannot be started on its downward movement, or if, for any reason, the truck should move off center, after the pressure chamber has started to descend, the downward movement of the pressure chamber will be arrested and cannot be restarted until the truck has been recentered and a manual switch operated to effect continuance of the downward movement of the pressure chamber. In raising the pressure chamber, its upward movement is arrested automatically when the rim of the pressure chamber attains a predetermined height above the tops of the upright stocking forms mounted on the truck.

A switch controlled by the bell 10 in its descent causes the steam to be admitted to the bell when sealed on the base 1, and others actuated by pins on the turntables effect the shutting off of the steam from the pressure chamber, exhaustion of the steam from said chamber, raising said chamber and stopping rotation of the turntable when the last form of the series arrives at the center position of the gap in the nested group.

Starting of the chamber on its downward move-

ment and starting rotation of the turntables are effected through manually operated switches.

The sequence of operations is as follows: Assuming that the pressure chamber 10 is in its raised position and that the motor 66 which drives the turntables 35, 35 is stopped with one truck 50 and its turntables 35, on center in vertical alignment with the pressure chamber, as shown in Figs. 2 and 8, and the other truck 50 with its turntable 35 in the stripping and reloading position, as shown in Figs. 2, 5 and 7, with the first board *a* of the series carried by this second truck in the center of the nest gap (see Fig. 5), the operator presses a button 102 (Fig. 19) to start the motor 12 for lowering the pressure chamber 10, and holds said starting button "in" until the pressure chamber begins its descent. If the turntable on the truck presumed to be in alignment with the pressure chamber 10 is off center, the chamber actuating motor 12 will not start. This is controlled by a pair of switches 103, 103, one for each of the trucks 50, 50 (see Fig. 15). When properly centered, a pin 104 (see Fig. 9) on the lower side of the truck 50 engages a switch operating lever 105 and swings it about its center into switch closing position. If neither of the switches 103, 103 is closed the circuit remains open, and if the truck moves from the center position permitting the lever 105 to swing back into its circuit breaking position, the motor 12 will stop and cannot again be started until the manually operable switch 102 is again closed.

Assuming that the truck is centered and remains in this position, the motor 12 continues to rotate the jack screws 7, 7 until the packing ring 22 in the rim 18 of the chamber 10 is compressed between the base of the groove 19 and the top of the sealing rib 20 on the base 1. This produces an over-load in the motor 12 which automatically stalls the motor and causes an overload circuit breaker 107 to open the circuit to the motor 12.

Just prior to the pressure chamber 10 becoming tightly sealed against the base 1, the descending chamber operates a switch 108 which closes the circuit to the solenoid 95 by which the pilot valve 85 is operated and causes the valve element 80 to open the steam passage 81 permitting live steam to flow from the feed line 78 into and through the pipe 76 to the interior of the pressure chamber.

The operator then directs his attention to the group or series of boards *a*, *b*, *c* . . . *u*, *w* and *x*, carried by the truck 50 which has previously been moved from beneath the pressure chamber 10 to the stripping and loading position on the framework of the machine.

With the board *a* in the center of the clearance gap as shown in Fig. 5, the operator strips and reloads this board and operates a foot switch 109 which starts the motor 66 by which the turntables 35, 35 are rotated. The operator continues to press the foot switch until the board *a* moves out of the center loading position in the clearance gap to the one side thereof while the board *b* moves into said centralized position. The operator may then remove his foot from the switch 109 and the rotation of the turntable 35 will continue intermittently, bringing the boards *c*, *d*, *e*, etc. into the centralized position successively.

When the sixteenth board *p* arrives at the centralized position, a pin 111 on the turntable 35 (see Figs. 15 and 17) engages a lever 112 and thereby trips a switch 110 which deenergizes the solenoid 95 and causes the valve element 80 to shift its position to close the live steam passage

81 and to open the exhaust steam passage 82, whereby the steam within the chamber 10 exhausts from the pipe 76 through the passage 82 to the pipe 79. In the meantime, the operator continues to strip and board hosiery at the centralized position in the clearance gap as the boards are automatically and intermittently moved into said position by the continued intermittent rotation of the turntable 35.

10 As the twentieth board *t* arrives at the centralized position in the clearance gap, a pin 113 on the turntable 35 engages a lever 114 of the raising switch 115 (see Figs. 15 and 17) which restarts the motor 12 in a reverse direction to its previous direction of rotation, which causes a reverse rotation of the jack screws 7, 7 and a consequent raising of the chamber 10 from the base 1.

As noted above, the upward movement of the chamber is arrested by the yoke 8 engaging a lever 116 (see Fig. 1) of a limit switch 117, operating this lever to open the circuit to the motor 12, whereupon upward movement of the chamber 10 ceases.

25 The operator in the meantime is continuing the stripping and reloading of the boards successively arriving at the centralized position in the clearance gap. When board *a* again arrives at this position a cam 118 (see Fig. 6) on the bottom of the turntable 35 depresses a plunger 119 which trips a switch 120. This opens the circuit to the motor 66 and stops rotation of the turntable 35.

The operator then releases the catch 75 which holds the truck 50 in fixed position against the stop 73 and pushes the truck 50 from the loading position into alignment with the raised bell 10. By pushing the one truck 50 into position beneath the raised bell-shaped pressure chamber 10, the truck 50 then occupying the position under the bell is moved outwardly to the stripping and loading position at the opposite side of the bell tower 3 to that from which the last loaded truck is moved.

The cycle of operation is then repeated, by the operator pushing the button 102 to bring the bell down into sealing position around the truck and the newly loaded hosiery forms which have just been moved into alignment with the chamber 10.

Should the jamming of the rim of the pressure chamber 10 against the base 1 to the extent of stalling the motor 12 be sufficient to resist starting of the motor 12 in a reverse direction to raise the bell 10, this condition may be readily overcome by installing compression springs 125, 125 at the opposite sides of the chamber 10 adjacent the screws 7, 7 respectively with a suitable head 126 mounted on the tops of the compression springs for engagement with shoulders 127 formed on or carried by the chamber 10. In descending, the springs 125 will be placed under compression to react in the raising of the bell and relieve the motor 12 of a portion of its load, whereby said motor will readily begin rotation in a reverse direction to raise said chamber.

65 An electrical circuit diagram incorporating the various switches above referred to is shown in Fig. 19. It is believed that the circuit as disclosed, is sufficiently clear to enable a skilled electrician to wire the circuit in the proper manner to achieve the results above noted; and, as the circuit per se is disclosed fully in a copending application, Serial No. 327,900 filed April 4, 1940, a detailed explanation of the circuit here is deemed unnecessary.

In order to prevent condensation which may

collect on the underside of the top 15 of the chamber 10 from dropping down on the hosiery, a funnel shaped plate 170 (see Fig. 3) is mounted below said top, above the upper ends of the hosiery supporting forms, and is provided with a depending pipe 171 which is axially disposed in the chamber 10.

The drip pipe 171 terminates above the top of a funnel 172 (see Fig. 6) which is carried by the truck 50. The funnel 172 is provided with a drain pipe 173 which is tapped into the upper end of a central bore 174 formed in the turntable post 40 and leads the condensation into the bottom of the chamber 10 below the truck 50 and in line with the mouth of the pipe 76 in the base 1, as shown in Fig. 9.

Various modifications of the arrangement involving the use of a single pressure chamber with a pair of turntables supporting series of stocking forms respectively are shown in the present instance, and wherein the turntables are retained with their axes in fixed relatively spaced relation to each other while the single bell-type pressure chamber is movable laterally from vertical alignment with one of the turntables into vertical alignment with the other of the turntables; whereby, during the stripping and re-loading of the forms on the exposed turntable, the forms on the other turntable are enclosed within the pressure chamber undergoing treatment in the manner previously noted.

In Figs. 37, 38 and 39 the single bell-shaped chamber is disclosed as being provided with a pair of laterally projecting vertically aligned bearings 139, 130 which are slidably mounted on a hollow rigid upright post 131 within which is vertically movable a counterweight 132 connected by a cable 133 with the bell-shaped pressure chamber 10a, said cable extending over a sheave 134 which is rotatably mounted on a swiveled bracket 135 at the upper end of the post 131. The bell-shaped chamber 10a may be raised and lowered manually or mechanically, and while in the raised position is adapted to be swung about the axis of the post 131 laterally from a position in alignment with one set of forms into alignment with the other relatively spaced set of forms.

In that form of the invention shown in Figs. 32, 33 and 34, a single bell-shaped pressure chamber 10b is connected by a cable 133b to a counterweight 132b over sheaves 134b, carried by an overhead trolley 136, which is adapted to move along a supporting rail 137 while said bell is in its raised position, for moving the bell laterally out of alignment with one set of forms into alignment with a second laterally spaced set of forms. In this instance, the raising and lowering of the bell 10b is manually performed.

In Figs. 35 and 36 a similar arrangement to that above noted is shown. However, in this instance the counterbalance 132b is replaced by a power hoist 138.

In each of the instances noted above the sealing of the rim of the bell with the base may be effected manually, by the use of the usual type of bifurcated lug on one of the elements and a clamp bolt pivotally connected to the other of the elements and having a hand nut threaded on the bolt for clamping against one side of the bifurcated lug when the bolt is swung into position between the two parts of the lug, such arrangement being common in securing heads to chambers in which a pressure is to be built up

and yet making the head readily removable from the chamber.

In the form of the invention shown in Figs. 26, 27 and 28 the single bell 10c is movably mounted in a tower 3c which, in turn, is mounted on a truck 140 arranged to travel on rails 139 for moving the bell 10c from position in alignment with one group of forms laterally into alignment with another group of forms carried by the turntable as above noted. In this instance the seal may be formed by the use of clamping bolts similar to those described above.

In that form of the invention shown in Figs. 29, 30 and 31 the single bell 10d is mounted in a tower 3d carried by a truck 140 movable on rails 139 in the manner above noted. In this instance, the tower truck is shifted laterally from one position to the other by means of an endless belt 141 adapted to be driven in opposite directions alternately by a motor 142. In this instance, the seal between the rim of the bell and the base is formed by the pressure screw 143 slidably mounted in a bridge element 144 which is pivotally mounted on one post 145 carried by the truck 140 and adapted to be swung from a position wherein the screw 143 is in axial alignment with the bell 10d into a position where the bell may be raised by cables 146, wound around drums 147, which are driven by a motor 148, said cables being located at opposite sides respectively of the bell 10d. When the bell is in lowered position around one of the groups of forms the clamping bracket 144 is swung about the post 145 until the clamping screw 143 is axially aligned with the chamber 10d, at which time a head 149 on the bracket 144 lies under a fixed collar 150 on a second post 151 which projects upwardly in the tower 3d. The screw 143 is slidably mounted in bearings 152, 153 formed on or carried by the swinging bracket 144. Suitable slot and key means are provided to prevent relative rotation between the screw and the swinging bracket.

Threaded on the screw between the bearings 152, 153 is a nut 154. The nut carries a sprocket 45 wheel 155 which is connected by a chain 156 to a sprocket wheel 157 which is rotatably mounted on the swivel posts 145 for the bracket 144. Connected to the sprocket 157 is a second sprocket 158 which is connected by a chain 159 to a sprocket 160 rotatably mounted on a bracket 161 carried by the truck 3d below the top of the base against which the bell seats. The sprocket 160 is provided with a crank 161 by which the nut 154 may be rotated to force the screw 143 and the bell 10d downwardly until a seal between the rim of the bell 10d and the top of the base 1d is effected.

In the form of the invention shown in Figs. 20, 21, 22 and 23 a pair of bells are employed to remain constantly in vertical alignment with two laterally spaced groups of stocking forms and turntables supporting the same, with the two bells being arranged to be moved vertically to positions clear of the upper ends of the forms and to be lowered into position around the forms wherein the rim of the bell will make sealing contact with the base supporting the turntable.

In the form of the invention shown in Figs. 20, 21 and 22 the two bells 10e, 10e' are counterbalanced by means of cables 164, 164', passing around sheaves 165 with the opposite ends of the cables connected at opposite sides respectively of the two bells 10e, 10e', at points adjacent the lower rim edges thereof, whereby when one bell

is in its raised position the other bell is in its lowered position and vice versa.

In that form of the invention shown in Fig. 23 the two bells may be counter-balanced as previously described, or independently movable by 5 jack screws etc., in the manner disclosed in Fig. 1. In this instance means is provided for quickly evacuating the steam from the interior of the lowered chamber prior to the raising of the chamber. In this instance the pipe 176 of each chamber 10f is connected with a live steam pipe 178 under control of a valve 180 and to an exhaust pipe 179 which is connected to a vacuum chamber 181 with a valve 182 provided in the line 15 between the pipe 176 and said tank. A vacuum pump 183 connected to said vacuum tank maintains said tank under the desired degree of vacuum, whereby, upon opening the valve 182 after the valve 180 has been closed, the steam within the lowered pressure chamber is evacuated rapidly into the vacuum chamber and from there by the pump 183 to exhaust.

If desired, the two bells 10f, 10f may be lowered at one and the same time and the valves 180, 180 opened simultaneously while the exhaust control valves 182, 182 and a live steam control valve 184 are all closed; whereby steam pressure in one chamber may be divided between and in the two, whereupon the valves may be set to exhaust the steam from one and introduce live steam into the other, thereby saving approximately 50% of the steam which otherwise would be directly exhausted into the chamber 181.

As shown in Fig. 24 the steam from the interior of the pressure chamber 10g may be rapidly exhausted by creating a vacuum in the tank 181g by condensing the steam therein with the valves 180g and 182g closed and then opening the valve 182g connecting the vacuum tank 181g with the interior of the pressure chamber 10g. As the steam enters the tank 181g it is intercepted or brought into contact with sprays of cold water 185g from the spray-head 186g which rapidly condenses the steam in the tank, and as the steam condenses and contracts in volume it creates a vacuum in the tank which rapidly draws the steam out of the interior of the pressure chamber 10g, it being understood that during such evacuation inlet of live steam to the interior of the pressure chamber 10g is prevented by closing of the valve 180g in the pipe 178g which connects the interior of the chamber 10g with the source of live steam. If desired, the chamber 10 may be provided with an inner wall 194 (see Fig. 25) to form an annular chamber 195 inside the outer shell 196 of the chamber and water spray heads 197 may be provided in the lower end of the annular chamber 195 to effect condensation and evacuation of the steam from the chamber 10, through suitable pipes 198.

In each of the previously described forms of the invention involving the use of the single bell, or each of the bells where more than one is used, the bell is capable of enclosing a relatively large group of forms, for example twenty-four forms, with each series mounted on a turntable and nested circumferentially thereof. In that form of the invention shown in Figs. 40, 41 and 42 a pair of relatively smaller bells 10h, 10h are adapted for respectively enclosing smaller groups of forms, for example twelve forms each, with the forms arranged in substantially parallel laterally spaced relation to each other within a relatively small horizontal area, making it pos-

sible to use bells of relatively small diameter. The forms in this instance may be individually pivotally connected to the bases 1h, 1h or slidably mounted thereon for individual movement to a position out of alignment with the remainder of the series to facilitate stripping and reboarding.

In this instance, the two bells 1h, 1h are operated simultaneously into their raised and lowered positions, and for this purpose are connected by a yoke 8h which, in turn, is connected at its center to a jack screw 1h, which is axially movable in a hollow post 187 carried by the base 1h and projecting vertically therefrom intermediate the two bells. The lower end of the jack screw 1h passes through and has threaded engagement with a nut 188 which is mounted between vertically spaced bearings 189. The nut 188 is provided with a pulley or sprocket wheel 190 which is connected by a belt or chain 191 to a smaller pulley or sprocket 192 secured to the shaft of a reversible motor 193, whereby the two bells may be raised and lowered and the seals made and broken between the rims of the bells and the base by power supplied from the motor 193.

Obviously single bells of small diameter, co-operating with parallel groups of boards, may be used with the small bells operated independently simultaneously or alternately into the raised and lowered positions in manners previously described.

I claim:

1. A device for treating a plurality of textile articles respectively mounted on a plurality of vertical forms, comprising a series of vertical forms, a vertical chamber, a common carrier supporting said series in a compact group for simultaneous confinement in said chamber, means for supporting said carrier and said chamber for relative vertical movement to enclose and expose said forms, and means attaching said forms to said carrier for movement separately to a stripping and reloading position relative to the remainder of said group when exposed.

2. A device for treating a plurality of textile articles respectively mounted on a plurality of vertical forms, comprising a series of vertical forms, a vertical chamber, a common carrier supporting said series in a compact group for simultaneous confinement in said chamber, means for supporting said carrier and said chamber for relative vertical movement to enclose and expose said forms, said carrier being rotatably mounted to bring said forms successively to a stripping and reloading station when exposed.

3. A device for treating a plurality of textile articles respectively mounted on a plurality of vertical forms, comprising a series of vertical forms, a vertical chamber, a common carrier supporting said series in a compact group for simultaneous confinement in said chamber, means for supporting said carrier and said chamber for relative vertical movement to enclose and expose said forms, means for moving said carrier intermittently to bring said forms successively to a stripping and reloading station when exposed, and means attaching said forms to said carrier for movement of each form separately into a clear position with respect to the remaining forms of said plurality at said stripping and loading station.

4. A device for treating a textile article on a vertical form, comprising a vertical form, a ver-

tical chamber, means for supporting said chamber for vertical movement relative to said form, means for supporting said form for lateral movement in opposite directions alternately relative to said chamber to enclose and expose said form alternately, and means for sealing the chamber when enclosing the form.

5. A device for treating textile articles respectively mounted on vertical forms, a pair of vertical forms disposed in laterally spaced relation to each other, a vertical chamber, means for supporting said forms for independent relative movement laterally into and out of vertical alignment selectively with said vertical chamber, means supporting said chamber for vertical movement relative to the form aligned therewith to enclose and expose said aligned form, and means for sealing the chamber when enclosing a group of forms.

6. A device for treating textile articles on two groups of vertical forms, comprising two independent groups of vertical forms, a vertical chamber, means supporting said groups and chamber for relative lateral movements selectively into and out of vertical alignment of one or the other of said groups with respect to said chamber, means supporting said groups and said chamber for relative vertical movements for enclosing and exposing said groups with respect to said chamber, and means for sealing the chamber when enclosing a group of forms.

7. A device for treating textile articles on two groups of vertical forms, comprising two independent groups of vertical forms, a vertical chamber, means supporting said form groups for lateral movement alternately into and out of vertical alignment with said chamber, means supporting said chamber for vertical movement relative to one of said groups of forms vertically aligned therewith to enclose and expose said aligned group, and means for sealing the chamber when enclosing a group of forms.

8. A device for treating textile articles on groups of vertical forms, comprising a plurality of groups of vertical forms, a carrier for each group, a vertical chamber, means supporting said carriers and said chamber for selective alignment between one of said groups and said chamber, means for raising and lowering said chamber relative to the group aligned therewith, means for admitting and exhausting treating fluid to and from said chamber while enclosing said aligned group, and means for sealing the chamber when enclosing a group of forms.

9. A device for treating textile articles on groups of vertical forms, comprising a plurality of groups of vertical forms, a carrier for each group, a vertical chamber, means supporting said carriers and said chamber for selective alignment between one of said groups and said chamber, means for raising and lowering said chamber relative to the group aligned therewith while leaving another of said groups exposed, the carrier of said exposed group being free for movement to bring the individual forms of the group successively to a stripping and loading station, means for admitting treating fluid to said chamber while enclosing said aligned group, and means controlled by predetermined movements of said exposed carrier for exhausting said fluid from said chamber.

10. A device for treating textile articles on groups of vertical forms, comprising a plurality of groups of vertical forms, a carrier for each group, a vertical chamber, means supporting said

carriers and said chamber for selective alignment between one of said groups and said chamber, means for raising and lowering said chamber relative to the group aligned therewith while leaving another of said groups exposed, the carrier of said exposed group being free for movement to bring the individual forms of the group successively to a stripping and loading station, means

10 moves to a stripping and loading station, means controlled by the descent of said chamber for admitting treating fluid to said chamber while enclosing said aligned group, and means controlled by predetermined movements of said exposed carrier for exhausting said fluid from said chamber.

11. A device for treating textile articles on groups of vertical forms, comprising a plurality of groups of vertical forms, a carrier for each group, a vertical chamber, means supporting said carriers and said chamber for selective alignment

20 between one of said groups and said chamber, means for lowering said chamber relative to the group aligned therewith while leaving another of said groups exposed, the carrier of said exposed group being free for movement to bring the individual forms of the group successively to a stripping and loading station, means for admitting treating fluid to said chamber while enclosing said aligned group, means controlled by predetermined movements of said exposed carrier for exhausting said fluid from said chamber, and means also controlled by said movements of said exposed carrier for effecting raising of said chamber to expose said aligned group.

12. A device for treating textile articles on groups of vertical forms, comprising a plurality of groups of vertical forms, a carrier for each group, a vertical chamber, means supporting said carriers and said chamber for selective alignment of the chamber with one of said groups, means for lowering said chamber around said aligned group, means controlled by the descent of said chamber for admitting treating fluid to the interior thereof, means controlled by predetermined movements of an exposed group carrier for exhausting said fluid from said chamber, and means also controlled by said carrier movements for raising said chamber to expose said aligned group.

13. A device for treating textile articles on groups of vertical forms, comprising a plurality of groups of vertical forms, a carrier for each group, a vertical chamber, means supporting said carriers and said chamber for selective alignment of the chamber with one of said groups, means for lowering said chamber around said aligned group, means controlled by the descent of said chamber for admitting treating fluid to the interior thereof, means controlled by predetermined movements of an exposed group carrier for exhausting said fluid from said chamber, means also controlled by said carrier movements for raising said chamber to expose said aligned group, and means for intermittently effecting said movements of said exposed group carrier.

65 14. A device for treating textile articles on
groups of vertical forms, comprising a plurality
of groups of vertical forms, a carrier for each
group, a vertical chamber, means supporting said
carriers and said chamber for selective align-
70 ment of the chamber with one of said groups,
means for lowering said chamber around said
aligned group, means controlled by the descent of
said chamber for admitting treating fluid to the
interior thereof, means controlled by predeter-
75 mined movements of an exposed group carrier for

exhausting said fluid from said chamber, means also controlled by said carrier movements for raising said chamber to expose said aligned group, means for intermittently effecting said movements of said exposed group carrier, means for initiating said intermittent movements of said exposed group carrier, and means operable by said exposed group carrier for terminating said movements thereof.

15. A device for treating textile articles on groups of vertical forms, comprising a plurality of groups of vertical forms, a carrier for each group, a vertical chamber, means supporting said carriers and said chamber for selective alignment of the chamber with one of said groups, manually operable control means for lowering said chamber around said aligned group, means controlled by the descent of said chamber for admitting treating fluid to the interior thereof, means controlled by predetermined movements of an exposed group carrier for exhausting said fluid from said chamber, means also controlled by said carrier movements for raising said chamber to expose said aligned group, means for intermittently effecting said movements of said exposed group carrier, manually operable control means for initiating said intermittent movements of said exposed group carrier, and means operable by said exposed group carrier for terminating said movements thereof.

16. A device for treating textile articles on vertical forms, comprising a series of vertical forms, a vertical chamber, a base supporting said forms below said chamber, means for lowering said chamber around said forms to enclose said forms and produce a fluid tight seal between said chamber and said base and for elevating said chamber to expose said forms, and power storage means loaded by the descent of said chamber into said sealing relation to said base for reacting during reversal of said raising and lowering means to assist said raising means in initiating raising movement of said chamber and the breaking of said seal.

17. A device for treating textile articles on vertical forms, comprising a series of vertical forms, a vertical chamber, means for lowering said chamber around said forms and subsequently raising said chamber to expose said forms, means for nesting a plurality of said forms about a common center into small compass for enclosure by said chamber, means for separating normally closely adjacent forms in said nesting to provide a gap therein for stripping and loading of a single form of said plurality while exposed, means for centering said forms successively in said gap, and means for turning each form into a predetermined position relative to said common center as said form moves from said gap-center into nesting position relative to the remaining forms of said plurality.

18. A device for treating textile articles on vertical forms, comprising a series of vertical forms, a vertically operable chamber open at one end solely for passage of said forms into and out of the interior of said chamber, a horizontally movable truck supporting said series of forms in a closely compacted group for movement of the entire series simultaneously into and out of vertical alignment with said vertically operable chamber, and means for sealing the chamber when enclosing a group of forms.

19. A device for treating textile articles on vertical forms, comprising a series of vertical forms, a vertically operable chamber open at one

end solely for passage of said forms into and out of the interior of said chamber, a horizontally movable truck supporting said series of forms in a closely compacted group for movement of the entire series simultaneously into and out of vertical alignment with said vertically operable chamber, means for centering said truck under said chamber preparatory to lowering of the latter around said forms, and means for sealing the chamber when enclosing a group of forms.

20. A device for treating textile articles on vertical forms, comprising a series of vertical forms, a vertically operable chamber, a horizontally movable truck supporting a group of said forms for movement into and out of vertical alignment with said vertically operable chamber, means for centering said truck under said chamber preparatory to lowering of the latter around said forms, and safety means for preventing and stopping descent of said chamber relative to said forms upon failure of said centering of said truck relative to said chamber.

21. A device for treating textile articles on vertical forms, comprising a series of vertical forms, a vertically operable chamber for enclosing and exposing said forms, a truck movable horizontally below said chamber into and out of vertical alignment with said chamber, and a turntable rotatably mounted on said truck for supporting said forms for rotary movement about a common axis relative to said truck when not aligned with said chamber to permit the forms to be moved successively to a stripping and loading position.

22. A device for treating textile articles on vertical forms, comprising a series of vertical forms, a vertically operable chamber for enclosing and exposing said forms, a truck movable horizontally below said chamber into and out of vertical alignment with said chamber, a turntable rotatably mounted on said truck for supporting said forms for rotary movement about a common axis relative to said truck when not aligned with said chamber to permit the forms to be moved successively to a stripping and loading position, and means spaced from said chamber for rotating said turntable under the last stated condition and disengageable to prevent said rotation when said truck is aligned with said chamber.

23. A device for treating textile articles on vertical forms, comprising a series of vertical forms, a vertically operable chamber for enclosing and exposing said forms, a truck movable horizontally beneath said chamber into and out of vertical alignment therewith, a turntable on said truck supporting said forms, means on said truck for intermittently rotating said turntable including a rotary element projecting from said truck, and a rotary element disposed at all times at the limit of outward horizontal movement of said truck for engagement and disengagement with the gear on said truck for driving said turntable solely when said truck is in its extreme outward position with respect to said chamber.

24. A device for treating textile articles on vertical forms, comprising a series of vertical forms, a turntable rotatable in a horizontal plane about a vertical axis, a series of arms pivoted to said turntable about axes substantially parallel to the axis of said turntable for supporting said forms respectively, and a stem on each form mounted in the outer end of its supporting arm with its axis substantially vertical to afford rotation of the form relative to the arm.

25. A device for treating textile articles on

vertical forms, comprising a series of vertical forms, a turntable rotatable in a horizontal plane about a vertical axis, a series of arms pivoted to said turntable about axes substantially parallel to the axis of said turntable for supporting said forms respectively, a stem on each form mounted in the outer end of its supporting arm with its axis substantially vertical to afford rotation of the form relative to the arm, and means limiting said rotation of said form relative to said arm about the axis of said stem.

26. A device for treating textile articles on vertical forms, comprising a series of vertical forms, a turntable, a series of arms pivoted to said turntable for supporting said forms respectively, a stem on each form rotatably mounted in the outer end of its supporting arm to afford rotation of the form relative to the arm, a projection on the inner end of each arm, and a fixed projection in the path of movement of said arm projection about the axis of said turntable for swinging each arm and its associated form into a predetermined position upon relative rotation of said turntable relative to said fixed projection.

27. A device for treating textile articles on vertical forms, comprising a series of vertical forms, a turntable, a series of arms pivoted to said turntable for supporting said forms respectively, a stem on each form rotatably mounted in the outer end of its supporting arm to afford rotation of the form relative to the arm, a projection on the inner end of each arm, a fixed projection in the path of movement of said arm projection about the axis of said turntable for swinging each arm and its associated form into a predetermined position upon relative rotation of said turntable relative to said fixed projection, and a fixed cam engageable with each arm during said rotation of said turntable to position said arm projections for proper engagement with said fixed projection.

28. A device for treating textile articles on vertical forms, comprising a series of vertical forms, a turntable, a series of arms pivoted to said turntable for supporting said forms respectively, a stem on each form rotatably mounted in the outer end of its supporting arm to afford rotation of the forms relative to the arm, a projection on the inner end of each arm, a fixed

projection in the path of movement of said arm projection about the axis of said turntable for swinging each arm and its associated form into a predetermined position upon relative rotation of said turntable relative to said fixed projection, a fixed cam, and a finger on each form stem for engagement with said fixed cam to turn said forms relative to their respective supporting arms upon rotation of said turntable relative to said fixed cam.

29. A device for treating textile articles on vertical forms, comprising a series of vertical forms, a turntable, a series of arms pivoted to said turntable for supporting said forms respectively, a stem on each form rotatably mounted in the outer end of its supporting arm to afford rotation of the form relative to the arm, a projection on the inner end of each arm, a fixed projection in the path of movement of said arm projection about the axis of said turntable for swinging each arm and its associated form into a predetermined position upon relative rotation of said turntable relative to said fixed projection, a fixed cam engageable with each arm during said rotation of said turntable to position said arm projections for proper engagement with said fixed projection, a second fixed cam, and a finger on each form stem for engagement with said second fixed cam to turn said forms relative to their respective supporting arms upon rotation of said turntable relative to said fixed cam.

30. A device for treating textile articles on vertical forms, comprising a series of vertical forms, a turntable, a series of arms pivoted to said turntable for supporting said forms normally in lateral close adjacent relation to each other, a gear segment on each arm with a pitch arc struck from the axis of the arm pivot, a fixed gear segment with a pitch arc struck from the axis of rotation of the turntable, and means for rotating said turntable to effect successive engagement of said arm and fixed gear segments to swing said arms and their respective forms successively from one side of a wide angle gap in said lateral relationship through said angle to the opposite side thereof upon rotation of the turntable relative to said fixed gear segment.
